ROTARY ASSEMBLY OF INTERFITTING COUNTERPARTS

Frederick W. Tellkamp, Woodhaven, N. Y.

Application April 7, 1944, Serial No. 529,918

6 Claims. (Cl. 74—434)

This invention relates to rotors, to rotary bodies and to assembly bodies, in the class of machine elements; and inasmuch as it is applicable to various uses and modifications, and consists mainly in the shape of each of its counterpart elements and the assembly of same into the form of a wheel or rotor, I choose to call it a rotary assembly of interfitting counterparts.

The main object of this invention is to provide three substantially counterpart elements of such form or shape that they are capable of being interfitted into the form of a wheel, rotor, pulley, substantially circular magnet, frictional gear, or toothed gear.

Other objects and important features are pointed out or implied in the following description in connection with the accompanying drawing in which:

Fig. 1 is a side elevation of an assembly especially designed for use as a triplex magnet mounted on an axle for rotation.

Fig. 2 is a side view of one of the three counterpart metal elements shown interfitted in Fig. 1.

Fig. 3 is a lower-edge view of the element shown in Fig. 2.

Fig. 4 is a side elevation of a modification in which the counterpart elements are shown as of wood and have their arcuate portions adjoined so the periphery is continuous; a modified form of hub also being shown with an axle therein.

Fig. 5 is a side elevation of one of the counterpart elements shown interfitted in Fig. 4.

Fig. 6 is a sectional view taken along the line 6—6 of Fig. 5, adjoined to a similar second element for indicating how the width of the periphery may be increased for increasing traction, as when used as a pulley or as a ground-wheel.

Referring to the drawing in detail, wherein, similar reference-numerals refer to similar parts throughout the several views, the invention is described in detail as follows:

Since each of the three elements or integral units 1 are not only similar, but are counterparts, they are each similarly identified; and each is substantially U-shaped and consists of an intermediate bar or relatively long portion 1a, and two relatively short arcuate portions 1b that form the magnetic poles when magnetized by any appropriate means (not shown). The bar 1a of each unit 1 is diagonally cross-notched at 1c to form pairs of shoulders or walls 1d. These notches terminate at relatively thin portions 1f, the thickness of which is substantially equal to the depth of the adjacent notch and of each similar notch, while the width of each notch (be-

tween walls 1d) is substantially equal to the width of the respective relatively thin portions 1f; in other words, each notch 1c is equi-lateral and equi-dimensional with the respective inner surfaces of the respective thin portions 1f. Therefore, when interfitted as shown in Fig. 1, each pair of shoulders or walls 1d fit closely against two opposite edges of one of the relatively thin portions 1f; therefore there is mutual interfitting of two relatively thin portions and two pairs of shoulders at each joint between elements 1.

Each notch 1c is adjacent to a respective one of the arcuate elements 1b, and its walls 1d are inclined at about 30 degrees away from the adjacent portion 1b, this being of vital importance in effecting the interfitting of the three elements 1 so as to produce a substantially annular rim of the portions 1b supported by the equilateral triangle composed of the three bars 1a; and though it is quite practical to interfit these parts so tightly that they can be frictionally or clampingly secured together and to fit a shaft of triangular cross-section in the triangular central opening, a more practical safe and economical means of securing them in their interlocking arrangement is provided in connection with a shaft or axle 8 that is secured in an externally screw-threaded sleeve 9 whose periphery touches the centers of the three bars 1a. Two washers 10 are fitted around the sleeve 9 and against opposite sides of the triangular assembly, and two nuts 11 are screwed onto the sleeve 9 and combine therewith to exert a clamping effect on the flush surfaces of the three bars 1a. Approximately one-half of the nearer washer and nut is broken away to disclose parts or the farther washer that has other parts indicated in the arcuate dotted line. When this device (of Fig. 1) is magnetized, it is susceptible of many uses such as those of a magneto, make-and-break rotor, or rotary traction feeder or injector for pushing and pulling metal bars, sheets, strips, cables etc., by contact therewith of its periphery while it is being rotated.

In the wooden devices shown in Figs. 4, 5 and 6, the U-shaped elements are shown at 12, their intermediate bars at 12a, their arcuate portions at 12b, their notches at 12c, their shoulders or walls at 12d, their relatively thin portions at 12f, and they have interlapped beveled extensions of the arcuate elements at 12b1 provided with offsets or shoulders 12b2 that interlock in the assembly for effecting adequate rigidity of the continuous rim or annulus that is supported by the triangular arrangement of the bars 12a which serve the usual function of spokes and hub-connection

while being exceedingly strong and rigid. While screws 13 are shown as an effective means of securing the interlapped ends 12b1 together, other or additional securing means (glue for instance) may be employed therefor. Attention is directed to the fact that the wood-grains cross each other in each pair of interlapped ends 12b1, so these joints are exceedingly strong. The same applies to the joints where the relatively thin parts 12f interengage with one another, and these may be secured with glue and/or screws 14. For safety, all screw-heads are countersunk, including those of screws or bolts such as shown at 15 that connect the hub-members 16 to the centers of the bars 12a. The upper part of the nearer member 16 is broken off to disclose the construction of these two members, especially the shoulders or seats 16a that fit against the middle parts of the respective bars 12a. A part of one of the bars is broken away at right of the axle 17, to show one of the seats 16a more clearly. Any number of holes 12x may be provided to secure gear-teeth in place if desired.

While it is essential that all the elements 7 be substantially or broadly counterparts of one another, it is not essential that they be exact or absolute counterparts as shown in Fig. 1, and the same is true of the elements 12; for whereas, each of these elements are here shown with their notches in opposite sides of the intermediate bar, it is only essential that one element 7 and one element 12 be thus constructed, while each of the correlated U-shaped elements may have both notches in the same side; and while the forms shown have advantage of minimum cost in forming these elements, and in interlocking them in the assembly, the operation of assembling and interfitting them may be simplified and made easier by having only one of the correlated U-shaped elements with notches in its opposite sides.

Therefore, the invention is not confined or restricted to the precise forms shown, and specifically described in the foregoing, nor to any specific materials or uses, for numerous modifications may be made within the scope of the inventive ideas as implied and claimed.

The following is claimed as my invention:

1. In an element of a rotary assembly, a substantially U-shaped unit including a relatively long intermediate bar and relatively short arms which latter protrude laterally from the same side and opposite ends of said intermediate bar and are approximately parallel to one another, one end-portion of said bar having therein a notch

that extends diagonally thereacross and terminates at a relatively thin portion and at shoulders that diverge with respect to the adjacent one of said arms, the other end-portion of said bar having therein a notch that extends diagonally thereacross and terminates in a thin portion and at shoulders which diverge with respect to the arcuate portion adjacent thereto, each notch being of a proper width between its adjoining shoulders for receiving and interfitting with one of the relatively thin portions of a correlated one of said bars.

2. In the element defined by claim 1, the first-said notch being in the opposite side of the bar from the side in which the second-said notch is located.

3. The combination of three substantially counterpart elements such as defined in claim 1, said bars being arranged in triangular relation while the shoulders of the notches of each bar are engaged with lateral edges of relatively thin portions of correlated bars in the interfitting assembly.

4. The combination of three substantially counterpart elements having bars such as defined in claim 1, the notches of each bar being in opposite sides thereof, said bars being arranged in triangular relation while each bar has its end-portions respectively in front and in rear of end-portions of two of the three bars, the shoulders of the notches of each bar being engaged with lateral edges of relatively thin portions of two correlated bars of the three.

5. The combination of three substantially counterpart elements such as defined in claim 1, said elements having their intermediate bars arranged in triangular relation while the shoulders of each bar are engaged with the respective lateral edges of the relatively thin portions of two correlated substantially counterpart elements, and means engaged with the middle portions of said bars for securing them in said triangular relation.

6. The combination of three substantially counterpart elements including bars such as defined in claim 1, said bars being arranged to form an equilateral triangle while their shoulders and relatively thin portions are interengaged in interfitting relation, and means engaged with the middle portions of said bars for securing them in their triangular arrangement and for engagement with an axle in cooperative relation.

FREDERICK W. TELLKAMP.
